UNITED STATES PATENT OFFICE.

JOHN JACOB FURTHMILLER, OF ELKTON, SOUTH DAKOTA.

CURTAIN-HANGER.

1,253,368.

Specification of Letters Patent. Patented Jan. 15, 1918.

Application filed March 26, 1917. Serial No. 157,428.

To all whom it may concern:

Be it known that I, JOHN JACOB FURTHMILLER, a citizen of the United States, and a resident of Elkton, in the county of Brookings and State of South Dakota, have invented an Improvement in Curtain-Hangers, of which the following is a specification.

My invention is an improvement in curtain hangers, and has for its object to provide a device of the character specified, wherein blind and rod supporting brackets are provided, together with means for clamping the same to the casing of the window, without the necessity for nails or screws, or of tools.

In the drawings:

Figure 1 is a top plan view of the improved hanger, with parts in section.

Fig. 2 is a section on the line 2—2 of Fig. 1, looking in the direction of the arrows adjacent to the line.

Fig. 3 is a front view of a modified form of hanger in place.

Fig. 4 is a perspective view of one of the rod supporting brackets.

Fig. 5 is a section on the line 5—5 of Fig. 3, looking in the direction of the arrows adjacent to the line.

In the embodiment of the invention shown in Figs. 1, 2 and 4, a pair of blind and rod supporting brackets 1 is provided, the said brackets being elbow-shaped, and having bearing openings at their ends for engaging the trunnions of a blind supporting roller 2 and for a curtain rod 3. It will be noticed from an inspection of Fig. 1 that the ends of the brackets having the openings for the trunnions of the curtain rod are offset outwardly, as indicated at 4^a, so that the curtain rod is supported in front of the casement. The shape of the brackets permits the curtain rod also to take a position at a lower level than that taken by the blind.

These brackets are clamped against the casement by means of a pole 4. This pole fits at each end into cap-shaped ferrules 5 and 6, respectively, and at the end adjacent to the ferrule 6 the pole has an axial recess 7. A nut 8 is secured to the said end of the pole over the recess, and a screw 9 is threaded through the nut. The head of the screw engages the end of the cap, as shown, and it will be obvious that by turning the pole the ferrule 6 may be forced away from the pole to tightly clamp the brackets 1 against

the casing. In order to prevent marring of the casement, pads 10 of felt are arranged between the brackets and the casement, and other pads 11 are arranged between the ferrules and the brackets.

The improved brackets may be of the form shown in Fig. 4, that is having means for supporting both a blind and a curtain rod, or the curtain indicated at 12 in Fig. 3 may be connected directly with the pole 13, the rings of the curtain being slipped over the pole before the hanger is placed. The brackets 16 each have a bearing for engagement by the trunnion of the blind 17, and the pole 13 is constructed in the same manner as the pole 4, and clamps the brackets 16 in the same manner as the pole 4 clamps the brackets 1.

I claim:

1. A device of the character specified, comprising a pair of blind supporting brackets, a pole, a cap-shaped ferrule engaging each end of the pole, and a screw at one end of the pole and having threaded engagement therewith and engaging within the ferrule to clamp the brackets between the ferrules and the window casement, said pole having an axial opening for the screw, and cushioning pads of felt or the like between the ferrules and the brackets and between the brackets and the casement, each bracket comprising an elbow shaped member having at each end a bearing opening for the trunnion of a blind supporting roller and a curtain rod, respectively, one end of each bracket being offset outwardly.

2. A device of the character specified, comprising a pair of blind supporting brackets, a pole, a cap-shaped ferrule engaging each end of the pole, and a screw at one end of the pole and having threaded engagement therewith and engaging within the ferrule to clamp the brackets between the ferrules and the window casement, said pole having an axial opening for the screw.

3. A device of the character specified, comprising a pair of blind supporting brackets, a pole, a cap engaging each end of the pole, said pole being rotatable with respect to the caps and having means for forcing one of the caps away from the pole to clamp the brackets between the caps and the window casement.

JOHN JACOB FURTHMILLER.
